UNITED STATES PATENT OFFICE.

MILTON R. LOUDEN, OF JERSEY CITY, NEW JERSEY, ASSIGNOR TO THE
BIGELOW CARPET COMPANY, OF CLINTON, MASSACHUSETTS.

DESIGN FOR A CARPET.

SPECIFICATION forming part of Design No. 12,544, dated October 25, 1881.

Application filed July 29, 1881. Term of patent 3½ years.

To all whom it may concern:

Be it known that I, MILTON R. LOUDEN, of Jersey City, Hudson county, State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The background of this carpet has small T-shaped dots upon it, which appear clearly on the photograph. Upon the background so dotted are placed the several figures D, E, F, G, a, and b, said figures being so grouped with reference to each other that in a lozenge-like figure having in its angles four figures, D, there would be a figure, F, in the upper right and lower left side, a figure, G, in the upper left and lower right side, a figure, E, in the center, a figure, b, to the left of E, and a figure, a, to the right of E. These figures are of the configuration shown. The figure D has projecting downward on a short stem a ratchet-wheel-shaped figure, with beads in several of its corners, while from the right of the figure 30 D projects on a stem a peculiar leaf, and beyond that is another stem, which in turn has a downwardly-projecting cluster of leaves at the right. The figure E has a peculiar leaf on an angular stem, and projecting from this leaf a spray with a rosette-like flower, and further smaller leaves projecting therefrom. The figure F has at its lower part a rosette with leaves at the right and left thereof, said rosette having a vertical stem that appears to 40 rise from a cup-shaped or saucer-like figure. From the upper end of the stem of this rosette projects diagonally to the right a longer stem bearing at its ends a conventional flower, and a conventional leaf of peculiar shape, and 45 having in its center a prominent rosette, as

shown. The figure G has at its left and upper end a rosette, and from the same extends a stem to the right, on which stem are series of conventional leaves and flowers. Thistle-like floral ornaments connect also with the lower 50 part of the figure G, as shown. The figure a is a forked branch of conventional flowers, and the figure b represents a rosette-like flower on a stem having a downwardly-projecting leaf at its lower end, while other leaves project upward and to the right of the rosette. The figure b connects with the figure G by coming in contact with one thistle-like ornament of the figure G. The figure D also comes in contact with the figure G by reaching to 60 said thistle-like ornaments. All the other figures are isolated from each other.

I claim—

1. The design for carpets, consisting of the figure D, substantially as shown. 65
2. The design for carpets, consisting of the figure E, substantially as shown.
3. The design for carpets, consisting of the figure F, substantially as shown.
4. The design for carpets, consisting of the figure G, substantially as shown. 70
5. The design for carpets, consisting of the figure a, substantially as shown.
6. The design for carpets, consisting of the figure b, substantially as shown. 75
7. The design for carpets, consisting of the figures b and G, substantially as shown.
8. The design for carpets, consisting of the figures D and G, substantially as shown.
9. The design for carpets, consisting of the figures D G b, substantially as shown. 80
10. The design for carpets, consisting of the figures D E F G a b, substantially as shown.
11. The design for carpets, consisting of the figures D E F G a b, having T-shaped dots for 85 their background, substantially as shown.

MILTON R. LOUDEN.
